CLAIM

The ornamental design for a beverage generating kiosk, as shown and described.

DESCRIPTION

FIG. 1 is a perspective view of a beverage generating kiosk showing our new design.

FIG. 2 is a front elevation view of FIG. 1.

FIG. 3 is a left-side elevation view of FIG. 1.

FIG. 4 is right-side elevation view of FIG. 1.

FIG. 5 is a rear elevation view of FIG. 1.

FIG. 6 is a top plan view of FIG. 1; and,

FIG. 7 is a bottom plan view of FIG. 1.

In the drawings, the broken lines illustrate portions of the beverage generating kiosk that form no part of the claimed design. The oblique lines represent transparent or translucent surfaces such as the surfaces of hoppers of the beverage generating kiosk and a portion of the front face of the beverage generating kiosk.
